ELECTRIC CURRENT INTERRUPTER

Stuart O. Fiedler and Johan Bjorksten, Chicago,
Ill.; said Fiedler assignor to Bjorksten Research
Laboratories, Inc., Chicago, Ill.

Application October 27, 1945, Serial No. 625,050

6 Claims. (Cl. 200—32)

1

This invention relates to a device for producing an interrupted direct current, and, more specifically, to a device producing an interrupted current which is readily convertible to alternating current by means of a transformer.

Heretofore, several types of devices have been employed for this purpose, none of which has been entirely satisfactory. One type has been actuated by electromagnets moving an anchor intermittently, which, in turn, intermittently makes and breaks the contact. Another type has been dependent on the instant evaporation of liquid on passage of a large amount of current, such as is obtained, for instance, when current passes through a platinum needle immersed in sulfuric acid. Other types of devices have been based on revolving mechanical elements in which firm metallic bodies have intermittently contacted and been removed from each other, thereby making and breaking contacts. All of these prior devices have had the drawback that arcing would occur and that this arcing would cause a wear or oxidation of the contacting surfaces, which, in time, would interfere with the proper operation of the device.

An object of this invention is to provide a superior device for interrupting direct current, which is free from these disadvantages of prior art. Another object is a current interrupter in which the breaking contact is between two mercury electrodes. A further object is an interrupter where the breaking contact is between two electrodes of normally liquid sodium-potassium alloy. Another object is a current interrupter giving an interrupted current of predetermined wave form. Further objects will become apparent as the following detailed description proceeds, in which reference is made to the drawings, of which Figure 1 and Figure 3 are vertical sectional views, Figure 2 and Figure 4 partial sectional views, and Figures 5 and 6 are horizontal sectional views perpendicularly to Figures 1 and 3 and taken with a section through the center of the apparatus.

Referring to Figures 1 and 2, the particular embodiment of the invention shown in the drawings comprises a housing 1 made of ceramics, glass, plastic, or of any other insulating material of suitable mechanical properties and strength. Inside this case is a rotor 2, also made of an insulating material, and revolving around an axle 6. In this rotor are a number of insulating vanes 3 which are pressed against the circumference of the stator case, either by some suitable means such as springs, resilient material, or simply by

2

the centrifugal force generated by rotation. On this stator case, and slightly farther apart than the spacing between the vanes, are two tubulatures 7. The entire device is filled with a liquid metal. For this purpose we prefer to use a sodium-potassium alloy, since this combines a suitable liquid consistency and good conductivity with the lightness desirable for operation of high speed without generating excessive centrifugal pressures. However, instead of the sodium-potassium alloy, we may use mercury, gallium; or we could use a eutectic bismuth tin lead alloy, or pure alkali metals, although in that case it would be necessary to operate the device at a temperature above the congealing point of these substances, which will generally not be desirable.

The rotor is revolved at a fixed speed, dependent upon the frequency desired, by any constant speed driving device known to prior art.

When the rotor revolves, the vanes pass over the space between the two tubulatures 7, and break the electrical circuit between the terminals 5 which enter the liquid metal in the tubulatures. In construction, the space on the stator between the tubulatures may be recessed so that the vane in passing over it can decrease the current gradually so that it will give a sinusoidal wave form shown in Figure 2, or any other wave form desired. Figure 2 is a developed view of the inside of the stator 1 at the point where the tubulatures 7 open into it, and shows one of the possible forms of these apertures, designed to give a sinusoidal curve.

The sinusoidal form gives a favorable sine alternating current wave when passed through the transformer.

For operation on triple phase current, the case may have three sets of openings in it, or even more openings and vanes to give polyphase current of any variety or characteristics desired. Figure 2 shows a section through the tubulatures, and shows one of the possible forms which these may be given in order to provide a favorable curve current.

In another modification of the invention, the vanes protrude from apertures in the stator case, and are held by spring pressure or resilient backing against the rotor. In this case the tubulatures 7 in the stator case only represent entry points for the electrodes 5 and their form is irrelevant so long as their cross section is adequate for carrying the current contemplated. The rotor contains a series of bas-reliefs, the surface form of which is selected so as to cause the cross section of the liquid metal, and hence the value

of the current, to vary according to a predetermined pattern, as shown, for example, in Figure 4, which represents the developed view of the rotor. When the stator vanes 3 which separate the electrodes pass over one of the points 11 where the indentations are closed, the current will be interrupted. When a stator vane passes over the point 12 where the indentation is widest, the flow of the current will be at a maximum, and between these points a moderate amount of current will flow so that the resultant curve will be sinusoidal or may have any other desired wave form. Figure 5 more clearly shows the axle 6.

Obviously, many types of mechanical modification of the invention are possible without departing substantially from its spirit and scope. Important features of the invention are the use of liquid metal in the current interrupter in such fashion that the interruption occurs between electrodes of liquid metal in the absence of any gas space where arcing or oxidation or evaporation could take place, and also the employment in such an interrupter of the very low specific gravity potassium-sodium alloy, which makes possible a very much lighter construction or faster operation than would have been possible by the use of much heavier metals, such as mercury. The precise proportions of sodium and potassium are secondary, so long as the alloy is liquid at the operating temperatures in view: for example, an alloy of equal amounts of sodium and potassium is suitable. This alloy is nearly 15 times lighter than mercury, which greatly reduces the centrifugal strains and stresses, making possible far lighter and less expensive construction than would have been required for the use of a liquid metal having higher specific gravity.

While in the example, a ceramic material was employed for stator or rotor, it is, of course, permissible to use any other construction material, including metals, provided these are covered with an insulating surface coating.

As for lubrication, we may depend on the liquid metal, filling the interspace 4 between rotor and stator, or on the inherent characteristics of the vanes, particularly if these are made of plastic material, or, particularly if the contacts are made on the rotor side of the liquid metal, on a separate lubricant medium, effective in a thin film, such as a sodium fatty acid salt. If the contacts are made on the stator side, we may employ graphite as the lubricant, as graphite is heavier than the alkali metal alloy and is thus fed to the periphery by centrifugal force. The tubulatures 7 in the stator 1 are then made sufficiently shallow to prevent a settling of the graphite, but will keep the graphite suspended by the turbulence created in these recesses by the rotary motion of the main body of the liquid metal. We may even pack these recesses 7 with graphite so that the contact is made between a graphite electrode and the revolving body of liquid alkali metal alloy.

While we prefer to employ recessed electrodes filled with liquid metal, or with a conducting lubricant such as graphite, we may also employ solid metal electrode inlays of any metal insoluble in the alkali metal alloy, said inlays being flush with the wall of the stator, and having a form selected to give a sinoid, or any other desired form and sequence of interruptions, as the revolving liquid metal and insulating vanes pass thereover in sequence.

While reference has been made repeatedly to a sodium potassium alloy, we understand that we may employ with substantially equal advantage any alkali metal alloy normally liquid at room temperature. The melting point curves of the various sodium-potassium alloys are well known in the art so that the selection is simple for any skilled chemist. Eutectic or low melting alloys with other alkali metals such as cesium, 10 lithium and rubidium may also be employed, and the addition of some percentage of nonalkali metal is within the scope of this invention, so long as said alloy is essentially an alkali metal alloy and is liquid at the operating temperatures contemplated. We may employ pure sodium or 15 potassium, depending on friction to generate the necessary heat to melt the metal, but this is not preferred, as a considerably heavier construction would then be required to withstand the strains in starting.

While reference has been made to members in the device as "rotor" and "stator," it is fully realized that these terms are relative, that the inner core may be fixed and the outer core brought to revolve, and that they may even both be brought to revolve countercurrently, for example, by a planetary drive, so that both members 1 and 2 become rotors.

The invention is thus of broad scope, and is not to be restricted, except by the claims, in which it is intended to cover all novelty inherent in the invention as broadly as possible in view of prior art.

Having thus disclosed our invention, we claim:

1. A current interrupting device comprising a rotor, a stator, said rotor and stator being of electrically insulating material and separated by an interspace filled with liquid metal, means for connecting said liquid metal with at least two outside electrodes, vanes slidably attached to the stator so as to form a tight fit against the rotor interrupting the electrical continuity of the said liquid metal and non-continuous indentations in the said rotor.

2. A current interrupting device comprising a rotor, a stator, an interspace between these filled with liquid metal, means for connecting said liquid metal with outside electrodes, said rotor and stator being of electrically insulating material; vanes slidably attached to the stator so as to form a tight fit against the rotor interrupting the electrical continuity of said liquid metal and non-continuous sinusoidal indentations of the said rotor.

3. A current interrupting device comprising, in combination, a stator case and a rotor revolving therein, both of electrically insulating material, a liquid metal between said stator and said rotor, vanes moving with said rotor in tight engagement with said stator, so as to completely interrupt the continuity of said liquid metal, excepting when passing over recesses in the stator case, and electrodes, spaced apart, contacting the said recesses, the said liquid metal being an alkali metal alloy.

4. As claim 2, the said liquid metal being an alkali metal alloy.

5. A current interrupting device comprising, in combination, two electrically insulating members revolving concentrically in relation to each other; a closed interspace between said members; a liquid metal filling said interspace; at least two insulating vanes separating said liquid metal in at least two portions; at least two electrodes con-

tacting said body of liquid metal so spaced that the said insulating vanes periodically interrupt the electrical connection between said electrodes.

6. As claim 5, said liquid metal comprising an alkali metal.
